CLAIM

The ornamental design for an mousetrap as shown and described.

DESCRIPTION

FIG. 1 is a perspective view of a mousetrap showing the first embodiment my new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of FIG. 1; and,

FIG. 10 is a partial enlarged view of FIG. 1.

The broken lines, forming a circle, show the boundary of the enlarged views in FIGS 1, 9, & 10 and form no part of the claimed design.
